UNITED STATES PATENT OFFICE

ROBERT L. TATHAM, OF CHICAGO, ILLINOIS

DISHWASHER

Application filed June 29, 1929. Serial No. 374,890.

This invention relates to dish washers, and its principal object is the provision of simple and highly efficient apparatus for washing dishes by discharging water with considerable force, in the form of jets or sprays, against dishes contained in a suitable tray. Another object is to provide pumping means whereby soapy water may be thrown upon the dishes during the washing operation, and thereafter clear water may be thrown upon them for the purpose of rinsing them after they have been washed.

Another object is to provide means whereby the jets or spray of water will be directed upon the dishes from all angles around a common center. Another object is to provide pumping means whereby the water may be taken from an ordinary kitchen faucet, sprayed upon the dishes and returned to the sink.

Another object is to provide simple means for mixing liquid soap with the water coming from the kitchen faucet and spraying the soapy water upon the dishes. Another object is to provide simple means whereby the tank in which the washing operation is performed may be readily removed from the remainder of the apparatus for any purpose whatsoever.

Other objects and advantages will occur in the course of this specification, and with all of said objects and advantages in view, this invention consists in the several novel features of construction, arrangement and combination of parts hereinafter fully set forth and claimed.

The invention is clearly illustrated in the drawings accompanying this specification in which—

Figure 1 is a perspective view of a dish washer embodying a simple form of the present invention and showing the same in connection with an ordinary kitchen sink;

Fig. 2 is a plan of the dish washer with its cover or lid removed;

Fig. 3 is a fragmental vertical cross section taken on the line 3—3 of Fig. 2;

Fig. 4 is a detail vertical fragmental section taken on the line 4—4 of Fig. 2;

Fig. 5 is a detail fragmental vertical sec-

tion showing the connections between a certain sprinkler head and a water supply pipe;

Fig. 6 is a detail horizontal section taken on the line 6—6 of Fig. 1; and

Fig. 7 is a fragmental vertical cross section taken on the line 7—7 of Fig. 6.

Referring to said drawings, which illustrate one embodiment of the present invention, the reference character 10 designates a case or cabinet which, as a preference, may be formed of side walls 11 united at their corners by upright corner pieces 12 which project down beyond the side walls in the form of short legs to which are secured castor wheels 13. The upper end of the case or cabinet 10 is open and is covered by a lid 14 hinged to the upper end of the case at one side and provided with a brace 15 pivotally connected at one end to the lid or cover and having a slot at its other end arranged to engage with a stud 16 on the side wall 11 to hold the lid in its raised position. When the lid is in down position, the cabinet top will serve admirably as a table.

Removably supported in the case or cabinet 10 is a tank 17 for containing the dishes during the washing and rinsing operations, which tank occupies the upper portion of the case and rests upon a suitable support, here shown in the form of an angle iron frame 18, which extends around the inner faces of the side walls of the case and is secured thereto by rivets, welding, or otherwise. The upper edges of the walls of the tank 17 are folded down upon the inner faces of the walls and then bent horizontally into the interior of the tank and back upon themselves, as seen in Fig. 4, to provide horizontal flanges 19 extending around the inner faces of the walls, and the lid or cover 14 is provided with downwardly projecting flanges, here shown as formed upon an angle iron bar 20, which extend around the inner faces of the walls of the tank 17, and together with the flanges 19 of said tank,

provide a water tight joint between the lid and tank which effectively prevents any water from being splashed out when the washer is in operation.

At one corner of the tank 17 is a reservoir

21 for a soapy solution, such as liquid soap, which reservoir may be formed, in part, of two corner portions of the tank 17 and a diagonally extending wall 23, soldered or otherwise secured to said corner portions of the tank walls. The bottom 24 of the tank 17 forms the bottom of the reservoir 21 and the diagonal wall 23 may be extended across the upper end of the reservoir, as at 25, to 10 form the top wall thereof. A filler opening is provided in the top wall 25 of the reservoir which is closed by a filler cap 26 threadedly or otherwise secured upon an upstanding nipple in which the filler opening is 15 contained.

20 Removably supported in the tank 17 is a basket or tray 27 for holding the dishes to be washed. Said basket or tray may be formed of lengths of wire bent up and secured together to provide the open-work bottom and sides of the basket, and, if desired, the basket may contain spaced upright wire members 28 between which flat dishes, such as saucers or plates, may be 25 stood edgewise during the washing operation. Brackets 29 secured to the inner faces of the walls of the tank 17 are provided for removably supporting the basket or tray 27 in the tank.

30 Below the tank 17 is a compartment 30 in which is contained the apparatus for pumping the water used for washing the dishes, and said pumping apparatus will now be described. Supported within the compartment 30, as, for instance, upon an angle iron frame 31 secured to the walls of the case 10, is a platform or other support 32, here shown as extending diagonally across the compartment 30, and upon said platform 35 are mounted an electric motor 33 and two water pumps 34 and 35, the shafts of which are connected to the motor shaft 36 and driven by the motor. The pumps are located one on each side of the motor, and 40 are held in fixed position with respect to each other by the base or platform 32. This arrangement also provides simple means whereby the electric motor may be centered with respect to the axes of the pumps and 45 permanently held in such centered position with relation thereto.

50 The pump 34 supplies water, under relatively high pressure, for washing and rinsing the dishes, and the pump 35 operates to 55 discharge water accumulating in the tank. Preferably, the pump 34 is in the nature of a positive gear pump in order to obtain sufficient pressure to discharge the water against the dishes at relatively high pressure. The pump 35 may be in the nature of a centrifugal pump, since its function is merely to discharge the water from the tank 60 into a kitchen sink or other receptacle.

65 To the intake end 39 of the pump 34 is secured a length of hose or flexible tube 40

which extends to one wall 11 of the case where it terminates in a coupling member 42 from which leads a removable extension 41 attached to the hose 40 by a companion coupling member, and said extension 41 terminates in a nipple or cup-like end 43 which is arranged to be slipped over the nozzle of an ordinary kitchen faucet 44 (see Fig. 1). From the discharge end of the pump 34 leads a length of hose of flexible tube 45 which leads upward towards the bottom 24 of the tank 17 and is provided upon its end with a clamp 46 and detachably secured upon a hose connection 47 that projects down from the center of the bottom wall 24 of the tank. The hose 45 communicates with a water spraying or sprinkler device 48 located in the tank (see Figs. 2 and 5) and from which the water is discharged upon the dishes, as will be hereinafter more fully set forth.

70 Leading from the bottom of the soap reservoir 21 is a pipe 49 controlled by a needle valve 50 (see Fig. 6) removably secured to one of the side walls of the case, and having a hand wheel 51 located upon the outer side of the case. The pipe 49 leads to a T-coupling 52 which is interposed between the inlet end 39 of the pump 34 and the hose 40. It is to be understood that ordinary small 75 pipes and fittings are employed for connecting the reservoir 21 with the T-coupling 52 at the pump 34, and, as a preference, a union coupling 53 is provided in the pipe 49, at one side of the needle valve 50 (see Fig. 6), whereby the pumping apparatus may be detached and removed for any purpose, and whereby the tank 17 may also be removed, if desired. When the tank is to be removed, the needle valve is detached from the wall of the tank. Normally the needle valve 50 is closed, but during the initial washing operation, it is opened to permit a quantity of liquid soap, contained in the reservoir 21, to be drawn into the pump 34 along with the water entering through the hose 40, so as to permit the soap to mix with the clear water, whereby the mixture is thrown upon the dishes.

80 The bottom 24 of the tank 17 slopes towards a drain point which may be located at one side of the tank, and at this lowermost drain point is an opening 55 (see Fig. 2) through which the water discharges from the tank. A hose connector, similar to the 85 hose connector 47, projects down from the drain opening and a hose or flexible tube 57 is removably secured to said hose connector and leads to the intake side of the pump 35. A screen is usually provided in the drain opening 55 to prevent solid matter from 90 passing to the pump 35. From the discharge side of the pump 35 leads a length of hose or other flexible tube 58 which extends to a side wall of the case, from which leads 95

an extension 59, coupled to the hose or tube 58 by a coupling 60 and having upon its terminal end a goose neck fitting 61 (see Fig. 1) which may be placed over the edge of an ordinary kitchen sink 62 to permit the water coming from the tank 17 to be discharged into the kitchen sink by the pump 35.

A door 63 (see Fig. 1) is provided at one side of the compartment 30 whereby access 10 may be had to said compartment for the purpose of inspecting the pumping apparatus. Said door may be provided with a lock 64, whereby the door may be locked to prevent any one from tampering with the 15 pumping apparatus.

The hose connector 47 may be secured to or formed as a part of a pipe connector 65, soldered or otherwise secured to the bottom 24 of the tank, and threadedly secured in 20 said pipe connector is a nipple 56 upon which is rotatably mounted the spraying or sprinkling device 48, above referred to. Said spraying device may be in the form of a plurality of pipes 66 threadedly secured 25 in a hollow head 67 and provided with lock nuts 68 which, when turned up tightly against the head 67, prevent unscrewing of the pipes 66. The ends of the pipes are closed by caps 69 and a number of nozzles 70 30 are provided along the lengths of the pipes 66, through which nozzles the water is discharged in the form of jets or sprays. It will be understood that by turning the pipes 66 in the head 67, the nozzles 70 may be 35 made to assume any desired angle of inclination with respect to the vertical, and that by directing the nozzles of one pipe 66 in one direction and the nozzles of the other pipe in the opposite direction, the spraying device 40 is caused to rotate when water is forced through said pipes and nozzles at relatively high pressure, and the water will be discharged against the dishes contained in the tray above the spraying device from all 45 angles around the axis about which the spraying device rotates.

The connection between the rotating spraying device and the nipple 65 may comprise a sleeve 71 rotatably mounted upon a 50 reduced neck portion 65^a of the nipple 65 and threadedly secured in the head 67. A washer 72 interposed between the upper end of the sleeve 71 and the upper out turned end of the neck 65^a of the nipple 65 prevents separation between the fitting and sleeve, whereby the sprinkler or spraying device may rotate on the nipple 65 without danger of becoming disconnected therefrom.

An extension cord 75 leads from the electric motor 33 and is provided with a switch 73 which may be attached to one of the walls 11 of the case. The extension cord has an attachment plug 74 upon its end which may be plugged into any suitable electric socket.

65 In the operation of the dish washer, the

dishes to be washed are arranged in the basket or tray 27 and the lid 14 closed down upon the case 10. The hose extension 41 being attached to the kitchen hot water faucet and the hose extension 59 being placed upon the kitchen sink, as shown, the water is turned on and the switch is closed, thereby starting the electric motor and setting the pumps 34 and 35 in operation.

During the initial washing operation, the 70 needle valve 50 is opened to permit a quantity of the liquid soap, contained in the reservoir 21, to enter the pump 34 and mix with the hot water coming from the faucet, but the valve 50 is closed soon thereafter, 75 thereby permitting clear water to be thrown upon the dishes. The pump 34 forces the water at a relatively high pressure through the nozzles 70 of the spraying device, which device is thereby caused to rotate at a relatively high rate of speed and the stream or jets of water are thereby directed towards the dishes from all angles around the axis of rotation of the spraying device, whereby 80 the dishes are thoroughly cleaned and rinsed.

As the water gathers upon the bottom of the tank 17, it escapes through the hose or flexible tube 57 and is discharged from the machine by the pump 35 through the hose 59 and hose extension 59 into the kitchen sink. When the rinsing operation is completed, the kitchen faucet is closed, and the switch opened to stop the pumping apparatus. When all the water has been 90 discharged from the tank 17, the hose connections with the sink and kitchen faucet are detached therefrom, and the dishes removed or left to dry therein.

To remove the tank 17, the union coupling 53 is disconnected, the valve 50 detached from the wall 11 of the case and the two lengths of hose 45 and 57 disconnected from the tank after which the latter may be lifted out of the case. To remove the pumping apparatus, the lengths of hose 40 and 58 are detached from the wall 11 of the case, the union coupling 53 disconnected and the lengths of hose 45 and 57 disconnected from the tank.

I claim:

1. In a dish washer, the combination of a case having a lower compartment, pumping apparatus therein embodying a pump having its intake end connected to a water supply conduit, a dish holding tank removably secured in said case above said compartment, a dish spraying device in said tank, a soap reservoir contained in said tank, a water conduit leading from the discharge end of said pump and connected releasably to the dish spraying device, and a conduit leading from said soap reservoir and connected releasably to the intake end of said pump, whereby the tank and soap

reservoir may be disconnected from the pumping apparatus.

2. In a dish washer, the combination of a case having a compartment for containing pumping apparatus, a motor driven pump mounted in said compartment, a flexible water supply pipe leading from the intake end of the pump and adapted to be connected to a faucet, a dish holding tank secured in said case, a spraying element in said tank and connected to the discharge end of said pump, a soap reservoir carried by said tank, and a valve controlled conduit leading from said soap reservoir to the intake end of said pump.

3. In a dish washer, the combination of a tank for containing dishes, a spraying device in said tank, a pump having a conduit leading from its intake end and provided with means for connection with a source of water supply, the discharge end of said pump being connected to said spraying device, a liquid soap reservoir, and a valve controlled conduit separately leading from said soap reservoir to the intake end of said pump, whereby to supply a limited amount of soap to the water entering the pump.

4. In a dish washer, the combination of a tank for containing dishes, a spraying device therein, a pump having a conduit leading from its intake end and provided with means of connection with a source of water supply, the discharge end of said pump being removably connected to said spraying device, a soap reservoir secured in said tank, a pipe line separately leading from said soap reservoir to the intake end of the pump, and a valve in said pipe line for limiting the supply of soap to the water entering the pump.

In testimony whereof, I have hereunto set my hand, this 26th day of June, 1929.

ROBERT L. TATHAM.
